UNITED STATES PATENT OFFICE.

FRANK BELLIS, OF CHICAGO, ILLINOIS.

ELECTRICAL CONNECTOR.

1,411,263.

Specification of Letters Patent. Patented Apr. 4, 1922.

Application filed December 9, 1920. Serial No. 429,435.

To all whom it may concern:

Be it known that I, FRANK BELLIS, a citizen of the United States, residing at Chicago, in the county of Cook and State of Illinois, have invented new and useful Improvements in Electrical Connectors, of which the following is a specification.

This invention relates to devices for making electrical connections, and more particularly to devices of this kind applicable to the ends of conductors, the object of the invention being to provide a very simple, strong and efficient connector which can be readily applied.

15 The object stated is attained by means of a novel combination and arrangement of parts to be hereinafter described and claimed, and in order that the same may be better understood, reference is had to the 20 accompanying drawing forming a part of this specification.

In the drawing Figure 1 is a side elevation of one form of the device; Fig. 2 is a plan view thereof; Fig. 3 is an end view; Fig. 4 25 is a side elevation showing another embodiment of the invention; Fig. 5 is a plan view thereof, and Fig. 6 is an end view.

The device shown in Figs. 1, 2 and 3 of the drawing comprises a split sleeve 10 having 30 an integral arm 11 extending lengthwise from one of its ends and carrying a cam clamp 12. The outer end of the arm 11 is bowed transversely, as shown at 13, to form a seat for a conductor wire, and it is also 35 formed with upturned ears 14 between which the cam 12 seats and to which it is pivoted as shown at 15. The cam 12 is provided with a handle extension 16, which is connected to the arm 11 by a spring 17 tending 40 to swing the cam to gripping position.

The insulated wire with which connection is to be made will have its end embedded in the sleeve 10 and its bared end soldered to the arm 11. The other wire will be seated 45 in the trough-shaped end 13 of the arm 11, and upon swinging the cam 12 to grip said wire, the latter is securely held, the spring 17 keeping the cam in gripping position. It will also be evident that the harder the wire 50 is pulled, the tighter it will be gripped by the cam.

The device shown in Figs. 4 to 6 comprises a base plate 18 having a cam 19 at each end the same being similar to and operating in the same manner as the cam 12. The ends 55 of the plate 18 are reduced and made bowed in cross-section as shown at 20 to provide seats for two wires. The plate 18 is also bowed transversely to obtain greater rigidity.

Both forms of the invention will be found 60 especially useful on motor vehicles or other parts subject to much vibration, which latter will not result in looseness but tend to cause the wires to be gripped more tightly. The connection can also be easily and 65 quickly made.

The handle extension 16 projects rearwardly from the cam 12 and is positioned above the arm 11. It will also be noted in Fig. 2 that the handle extension is offset 70 laterally with respect to the longitudinal median line of the arm 11 so as to be entirely clear of the wire which is to be soldered to the arm. This arrangement also places the spring 17 out of the way of the wire, as well 75 as out of the way of the projecting inner end of the wire gripped by the cam 12, and keeps the device within reasonable dimensions.

I claim:

An electrical connector comprising a member having means for connection with a conductor, said member having an integral arm extending lengthwise from one of its ends, the outer end of the arm being bowed transversely to form a seat for a second conductor, and having upturned laterally spaced ears at its sides, a cam clamping member seating between the ears and pivoted thereto for engagement with the second-mentioned conductor, said cam having a rearwardly 80 projecting operating handle extension positioned above the aforesaid arm and offset laterally with respect to the longitudinal median line thereof, and a spring connected 85 to the handle extension for swinging the 90 cam to gripping position.

In testimony whereof I affix my signature.

FRANK BELLIS.
